FIG.4.

FIG.6.

Inventor
Matthew J. Haffey
by Fetherstonhaugh & Co
Atty's.

UNITED STATES PATENT OFFICE.

MATTHEW JOSEPH HAFFEY, OF TORONTO, ONTARIO, CANADA, ASSIGNOR OF ONE-FOURTH TO WILLIAM HARRY FREEMAN, OF TORONTO, CANADA.

EAR-TESTING DEVICE.

Application filed September 4, 1925. Serial No. 54,510.

My invention relates to improvements in ear testing devices, and the object of the invention is to provide a device by which the hearing of a person may be tested both as to 5 the pitch, timbre, time and force of a sound which his hearing is able to detect, and in which the pitch, timbre, time and force always remain constant, and it consists essentially of the arrangement and construction 10 of parts as hereinafter more particularly explained.

Fig. 1 is a front elevation of my device.

Fig. 2 is a cross sectional view taken on line 2-2 Figure 1.

Fig. 3 is a sectional view on line 3-3 Figure 1.

Fig. 4 is a sectional plan view.

Fig. 5 is a detail of the adjustable link connection 20*.

Fig. 6 is an enlarged detail view showing the means for supporting the graduated arm 32.

In the drawings like characters of reference indicate corresponding parts in each 25 figure.

1 indicates the main casing which is preferably provided with a hinge front 2.

3 is a bellows pneumatic, the top wall 4 of which forms the top wall of the casing when 30 the bellows is collapsed, the front 2 being connected to the front edge of the wall 4 by any suitable means thereby forming a container for my mechanism.

5 is a wind chest provided with reed openings 35 6 in which are located metal reeds 7.

8 is a reed chamber, a reed chamber being located under each reed. The front of each reed chamber is provided with an open mouth 9 through which the sound is emitted.

10 are a series of closures, the closure 10 being hingedly mounted as indicated at 11 above each mouth 9 and when in the vertical position forms a closure for such mouth, being held in the closed position by means of 45 a spring finger 12, a spring finger 12 being provided for each closure 10.

13 is a knob or other means by which the closure may be manually raised so as to open the mouth 9.

14 is a chamber which is formed in the wind chest 5 and provided with a rectangular opening 15 formed in the bottom wall of the wind chest 5 within the chamber 14.

16 is a slit opening formed in that portion

of the bottom wall 4* of the bellows 3 which 55 forms the top of the chamber 14.

17 is a valve hingedly connected to the wall 4* at 18, the valve 17 being adapted to be swung in and out of the covering position over the slit orifice 16.

19 is an arm rigidly extending from the valve 17.

20 is a supplemental pneumatic carried by the lower wall of the wind chest 5 so as to extend over the orifice 15.

20* is a link pivotally connected at its upper end to the arm 19 and connected at its lower end to an adjustable screw pin 21 preferably by forming a head 22 at the upper end of the pin with which the members of 70 the link 20* are clamped into engagement by a screw 23, such members being provided with small orifices 24 into which the side portions of the head 22 fit.

25 is a weight carried by an arm 26 secured to the lower wall of the pneumatic 20.

27 is a bar which is secured to the bottom wall of the casing so as to slide longitudinally preferably by means of a stud or screw 28* extending through a slot 28 formed in 80 the bar.

29 is a bracket carried by the bar 27 intermediate of its length. The outer end of the bar 27 is provided with an upturned end 27*.

30 is a lever pivotally mounted upon the bracket 29 as indicated at 31. 32 is a graduated arm preferably graduated to milimetres of water pressure provided with an orifice 33 across which extends a metal plate 34 provided with a V-notch 35 into which fits a knife edge 36 extending outward from the extension 27*.

37 is a link pivotally connected to the short end of the lever arm 32 and at its lower end to the outer end of the lever 30. The lever 30 is provided at its inner end with a longitudinal slot 38 into which extends a pin 39 carried by the lower wall of the pneumatic 20.

40 is an adjustable weight secured to the lever 30 by means of a set screw 41.

42 is a weight carried by the lever arm 32 so as to be slidable longitudinally thereof, the weight 42 being provided with a finger grip portion 42* and a pointer 43 coacting with the graduations of the lever arm 32.

Having described the principal parts in-

volved in my invention I will briefly describe the operation of the same.

When it is desired to test the hearing of a patient the device is placed in the position 5 shown in the figures of the drawing with the bellows 3 in the expanded position. In order to discover at what pitch a patient is able to hear a note, the closures 10 are successively swung to the open position indicated by dotted lines in Figure 2, one of these closures of course being opened at a time. The movable wall 4 of the bellows 3 is first manually depressed and then permitted to expand freely due to the pressure of the 15 spring and tending to draw air through the orifice 16. In order to hold the valve 17 in an adjusted partially open position the weight 42 is adjusted upon the arm 32 in order to more or less depress the same from 20 the dotted position shown in Figure 1. It will of course be understood that the farther the distance the weight 42 is moved from the fulcrum of the lever arm formed by the knife edge 35, the greater will be the depression of the long end of the lever thereby operating the short end of the lever to a greater or less extent to adjust the position of the pneumatic 20 and thereby opening the valve 17 to a more or less extent.

When the valve 17 is opened as above described, the air passes through the mouth 9 into the reed chamber and through the reeds 7 into the wind chest 5 and from thence into the chamber 14 and through the orifice 16 30 into the bellows 3 thereby causing the note to speak.

In order to vary the intensity or volume of the note to test the loudness which a person is able to hear, the weight 42 is adjusted upon the lever arm 32 thereby more or less depressing such arm at its free end and operating the lever 30 to a greater or less extent to adjust the position of the pneumatic 20 and through the link 20* and arm 19, adjust the position of the valve 17 40 to a more open position thereby permitting a greater volume of air to pass through the opening 16 increasing the volume of the notes sounded by the air passing through the 50 reed of the open valve chamber.

The patient is placed four metres from the instrument; the ear to be tested turned towards it and the other ear closed. The valve or closure 10 at the left hand side 55 corresponding to low C (thirty-two vibrations per second) is sounded by depressing the bellows 3 for one second. The weight on the scale is placed at ten millimetres. If the patient's hearing is normal 60 he will hear a note which is barely perceptible. If this is not heard the weight is moved along the scale increasing the loudness until the sound is heard. If the C° or low C used is imperceptible the next closure 65 corresponding to the low or F° (forty-two

vibrations per second), the C¹ (sixty-four vibrations per second) the C² (one hundred and twenty-eight vibrations per second) and the C³ (two hundred and fifty-six vibrations per second) are tried until an audible note 70 is reached. In this way the force of tone is accurately measured and the degree of dullness of hearing is finely calculated.

From this description it will be seen that I have devised a very simple device which will enable the hearing of a patient to be tested both as to the pitch of a sound which he is able to hear and also the volume of a sound which he is able to hear.

What I claim as my invention is:

1. An ear testing device comprising a main casing, a bellows supported in the casing, a wind chest having an air outlet communicating with the interior of the bellows and having a series of air inlets, a reed chamber having a sound emitting mouth leading from each inlet, a reed so positioned in each reed chamber that the air passes therethrough to the wind chest, a removable closure for each mouth, and means for controlling the volume 85 of air passing from the wind chest to the bellows to weigh the volume of tone as the air passes through the reeds.

2. An ear testing device comprising a main casing, a bellows supported in the casing, a wind chest having an air inlet communicating with the interior of the bellows and having a series of air outlets, a reed chamber for each outlet having a sound emitting mouth connected with each outlet, 100 a reed so positioned in each outlet that the air passes therethrough into the reed chamber to pass through the mouth thereof, a removable closure for each mouth, a valve for controlling the passage of air through 105 the inlet to the wind chest from the bellows, and graduated means for controlling the position of the valve.

3. An ear testing device comprising a main casing, a bellows supported in the casing, a wind chest having an air inlet communicating with the interior of the bellows and having a series of air outlets, a reed chamber having a sound emitting mouth connected with each outlet, a reed so positioned in the outlet that the air passes therethrough into the reed chamber to pass through the mouth thereof, a removable closure for each mouth, a valve for controlling the passage of air through the inlet to 110 the wind chest from the bellows, a lever arm fulcrumed in proximity to one end and suitably graduated, a weight adjustably mounted to move longitudinally of the lever arm to any of the graduated positions, and mechanism actuated by the opposite end of the lever arm for opening and closing the valve.

4. An ear testing device comprising a main casing, a bellows supported in the casing, a wind chest having an air inlet com- 130

municating with the interior of the bellows, and a series of air outlets, a reed chamber having a sound emitting mouth connected with each outlet, a reed so positioned in the 5 outlet that the air passes therethrough into the reed chamber to pass through the mouth thereof, a removable closure for each mouth, a valve for controlling the passage of air through the inlet to the wind chest from the 10 bellows, a lever arm fulcrumed in proximity to one end and suitably graduated, a weight adjustably mounted to move longitudinally of the lever arm to any of the graduated positions, a lever pivoted intermediately of its 15 length in the main casing at right angles to the aforesaid lever arm, a link connection between one end of such lever and the short end of the lever arm, and connecting actuating means between the opposite end of the 20 lever and the valve.

5. An ear testing device comprising a main casing, a bellows supported in the casing, a wind chest having an air inlet communicating with the interior of the

bellows and having a series of air outlets, a reed chamber having a sound emitting mouth connected with each outlet, a reed so positioned in the outlet that the air passes therethrough into the reed chamber to pass through the mouth thereof, a removable closure for each mouth, a valve for controlling the passage of air through the inlet to the wind chest from the bellows, a lever arm fulcrumed in proximity to one end and suitably graduated, a weight adjustably mounted to move longitudinally of the lever arm to any of the graduated positions, a lever pivoted intermediately of its length in the main casing at right angles to the aforesaid lever arm, a link connection between one 40 end of such lever and the short end of the lever arm, a pneumatic carried by the wind chest and communicating with the interior of the wind chest, an arm extending from the valve, and a link connection between the 45 outer end of the arm and the movable wall of the pneumatic.

MATTHEW JOSEPH HAFFEY.
